UNITED STATES PATENT OFFICE.

GARRETT VAN WAGENEN, OF MONROE, WISCONSIN.

BREAST-COLLAR IRON.

SPECIFICATION forming part of Letters Patent No. 406,069, dated July 2, 1889.

Application filed March 25, 1889. Serial No. 304,725. (No model.)

To all whom it may concern:

Be it known that I, GARRETT VAN WAGENEN, residing at Monroe, in the county of Green and State of Wisconsin, and a citizen 5 of the United States, have invented a new and useful Improvement in Breast-Collar Irons, of which the following is a specification, reference being had to the accompanying drawings, in which—

10 Figure 1 is a plan, partly in section. Fig. 2 is a vertical section at line 2 of Fig. 1. Fig. 3 is a section at line 3 of Fig. 1. Fig. 4 is a detail, being an end view and a front view of the collar against which one end of the 15 springs shown in Fig. 2 rests. Fig. 5 is a modification showing the springs in a different position from that in which they are shown in Fig. 2.

It is common to use a double harness having 20 breast-collars, and in use the pole of the vehicle swings from side to side frequently with considerable force, producing great strain upon the necks of the horses and upon the harness.

25 The object of my invention is to provide devices to be used with breast-collars for double driving by the use of which the sudden strain upon the necks of the horses and upon the harness will be greatly relieved, which I 30 accomplish as illustrated in the drawings and hereinafter described.

That which I claim as new will be pointed out in the claims.

In the drawings, A represents the front 35 part of a breast-collar, the same being shown in section in Fig. 1.

B is a yoke or breast-iron.

a is a piece of metal secured between two 40 parts of the breast-collar when the same is made, and the yoke B is secured to the collar by means of screws b, which pass through the iron a, through a portion of the collar, into and through the yoke, as shown in Fig. 1.

C is a rod, the ends of which are securely 45 fastened in the ears at the ends of the yoke B.

D is a casting, which is adapted at each end to receive a neck-strap c.

d are two ears, which are a part of the casting 50 D, and are provided with holes to receive the rod C.

e represents a strap connected at one end

with the bar f, which is a part of the casting D. This strap goes to the belly-band.

g is another strap connected at one end with the casting D. This strap goes to the neck-yoke.

h is a collar, which is connected with the rod C by means of a screw i.

j are two coiled springs—one on each side of the collar h, against which one end of each 60 spring rests. The other end of each spring rests against one of the ears d.

E is a cylindrical case, which covers the springs j and collar h. This case is provided with a hole, k, through which the screw i can 65 be inserted.

The yoke B, casting D, the springs j, collar h, and case E can be put together by placing the collar h and the springs within the case E and bringing the case to its proper position 70 between the ears d, and then inserting the rod C in place by passing it through one end of the yoke B, then through one ear d, then through the springs and collar h to the other end of the yoke, and then securing the rod in 75 place by riveting or otherwise. The case E can then be turned until the hole k therein registers with the hole in the collar h. The screw i can then be inserted into the collar h, and then the case can be turned so as to cover 80 the head of the screw in the collar h.

In use, as the pole swings from side to side, the strain upon the necks of the horses and also upon the harness will be greatly relieved by the action of the springs j, because the 85 iron D can swing from side to side somewhat, the ears d being pivoted on the rod C, and one or the other of the springs being compressed as the pole moves either to the right or to the left.

The springs will be retained in their normal position, (shown in Fig. 2,) except when moved to the right or left by the swinging of the pole.

In Fig. 5 I have shown a modification in 95 which the springs are located outside of the ears d. The operation of this modification is substantially the same as that before described, but with this form the springs cannot be covered, and hence it is much better 100 to locate the springs between the ears d than outside of them.

What I claim as new, and desire to secure by Letters Patent, is as follows:

1. The yoke B, in combination with a casting D, provided with ears d, rod C, and springs 5 on the rod, substantially as and for the purposes specified.

2. The yoke B, in combination with a casting D, provided with ears d, rod C, coiled

springs j, encircling the rod, collar h secured to the rod C, and case E, substantially as and for the purposes specified.

GARRETT VAN WAGENEN.
